UNITED STATES PATENT OFFICE

ARTHUR DICKERSON, OF SALT LAKE CITY, UTAH

JACK

Application filed August 11, 1928. Serial No. 299,086.

My invention relates to jacks and has for its object to provide a new and efficient jack for lifting automobiles and other similar objects.

5 A further object is to provide a lifting jack which will be economical to build, and one which will be exceptionally strong for its weight.

10 A still further object is to provide a jack which will be extremely easy to operate and one which may be raised to any given point before inserting it under the load to be lifted and which may be released to its initial position after it has been used and it is desired to 15 drop the load.

These objects I accomplish with the device illustrated in the accompanying drawings in which similar numerals and letters of reference indicate like parts throughout the 20 several views and as described in the specification forming a part of this application and pointed out in the appended claims.

In the drawings in which I have shown the best and most preferred manner of building 25 my invention, Figure 1 is a side elevation of the jack. Figure 2 is a side elevation from the reverse side of Figure 1. Figure 3 is a side view of one of the gears. Figure 4 is a face view of the same. Figure 5 is a side 30 view of another gear used in the jack. Figure 6 is a face view of Figure 5. Figure 7 is a side view of one of the friction members. Figure 8 is a face view of Figure 7. Figure 9 is a side view of the friction leather. Figure 35 10 is a face view of the same. Figure 11 is a plan view of the jack with the lifting arms removed. Figure 12 is a section of line 12-12 of Figure 2. Figure 13 is a section on line 13-13 of Figure 1. Figure 14 is an edge 40 view of the operating handle. Figure 15 is a plan view of the same.

In the drawings I have shown the base of the jack as A. Upon the top and near one side of the said base A, I provide a supporting frame B, with the lower end of the frame B formed into a foot C. The said frame B is cast integral with the base A and is curved upwardly and backwardly in the form of an arc with a hole bored through the top end 45 thereof in which a pivot pin 2 is carried. An

enlarged section B¹ is formed on the frame B to provide a friction surface. A triangular shaped lifting lever segment D is pivotally fulcrumed and supported by the said pin passing through the lever at the axis of the segment gear 3, which gear 3 is formed on the base of the segment D and with the said gear 3 forming the base of the triangular shaped segment D with teeth 4 formed on the face of the gear 3, and with a leg 5 securing the gear segment to form one side of the triangle and the other side or leg is formed by the leg 6, having an extension 7 formed into a lifting foot 8, the top side of which is formed into two curved receptacles 9 and 10 curved to fit under the side of an axle of an automobile. The under side of the lifting foot 8 is flat and rests upon the foot C when the jack is not being used or after it has been used and released.

Through the body of the frame B I provide a shaft 11, having a flanged gear wheel 12 screwed onto one end thereof with the teeth of the gear wheel 12 engaging with the teeth 4 of the gear segment 3, so that when the shaft 11 is rotated the gear 12 rotates and moves the lifting lever 8 up or down as necessary. On the other end of the said shaft 11, I provide a large gear wheel 14, and above and slightly to the rear of the shaft 11, I provide another shaft 15 which shaft 15 is also passed through the frame B and also has both ends threaded. One end of the said shaft 15 is screwed into the frame B and has a lock nut 16 screwed thereon to hold it securely in place. On the other side of the said frame B a flat circular friction washer 17 is placed and next to the washer I provide a friction plate 18, which plate 18 is adapted to be forced against the washer 17, forcing it against the side of the frame B and holding the washer and plate from rotating by the friction thereby created. The outer side of the said plate 18 is provided with a diametrical boss 19 formed thereon, which boss 19 is bored radially by the holes 20, in which holes 20 springs 21 are placed and locking dogs 22 are placed on top of the springs 21 with the springs adapted to hold the dogs outwardly. I then provide a flanged

wheel 23, which wheel is provided with a flange 24 on one side thereof with gear teeth 25 cut on the inner face of the flange adapted to be normally engaged by the dogs 22 when the springs 21 press them outwardly. The gear teeth 25 which are cut on the inner periphery of the flange 24 are cut with one side sloping and the other side somewhat radial making the teeth in the form of ratchet teeth so that the dogs 22 will engage with the teeth when moved in one direction and disengage by sliding over the sloping surface when the wheel 23 is rotated in the opposite direction. The outer periphery of the wheel 23 is provided with dog engaging teeth 25^a and another smaller gear wheel 23^a is formed on the other side of the wheel 23 with the teeth thereof adapted to engage with the teeth of the gear wheel 14. I then provide a toothed wheel 26 having a flange formed thereon adapted to pass into the bore of the wheel 23 and to press against the face of the plate 18. The bore of the wheel 26 is threaded and engages with the threads of the shaft 15 and when the wheel 26 is turned in one direction the threads thereon press it against the plate 18 forcing said plate against the washer 17 and preventing the component parts of the entire device from rotating. When it is turned in the opposite direction the plate is moved away from the washer and frame, releasing the device. A handle H is provided with an enlarged portion formed near one end thereof and having an elongated hole 27 therethrough, with the hole 27 encircling the flange of the wheel 26. A dog 28 is formed on one side of the handle H near the end thereof and is adapted to engage with the teeth of the wheel 26 and another dog 29 is formed above the hole 27 adapted to be engaged with the teeth 25^a of the wheel 23, so that when the handle is moved in one direction the dog 28 will engage with the teeth of the wheel 26 and will rotate the wheel when the handle is moved up and down, and when the handle is pushed forward the dog 29 is engaged with the teeth 25^a of the wheel 23 rotating it with its component parts.

The operation of my device is as follows: The handle is moved backwardly engaging the dog 28 with the teeth of the wheel 26 and the operator then moves the handle down locking the wheel inwardly forcing the plate against the washer 17 and frame B of the jack. The operator having locked the device for free rotation then pushes the handle forward engaging the dog 29 with the teeth 25^a of the wheel 23, he then presses downwardly on the handle and this motion rotates the wheel 23 and rotates the gear 23^a which in turn rotates the shaft 11, and the gear wheel 14 thereby moving the segment 3 and raising the lifting lever 7. When the lever has been raised sufficiently and it is desired to lower the lever the operator draws the handle back

until the dog 28 engages the teeth of the wheel 26 and then raises the handle moving the wheel 26 away from the plate 18 releasing the locking friction created thereby and the weight of the lever D will be sufficient to draw it down to the foot C and the jack is ready to be placed away or for further use.

Having thus described my invention I desire to secure by Letters Patent and claim:

In a jack the combination of a base member having a supporting frame formed integral therewith and with a foot formed near the lower end of the said frame; a lifting member pivoted to the free end of said frame, said lifting member being formed of a segment of a circular rack with one leg being extended and having lifting sockets formed on the top side thereof; a shaft through the main frame having a flanged gear wheel on one end thereof and a larger gear wheel on the other side of the frame with the teeth of the lifting member meshing with the teeth of the flanged gear wheel; another shaft passed through the frame having one end secured therein and having a friction locking means secured on the other side of the frame, said friction locking means consisting of a friction washer, a friction plate engaging one side of said washer, dogs carried in said friction plate, a flanged wheel having teeth on the inner face of the flange in which the dogs engage, and a gear on the outer side of said flanged wheel adapted to engage with the large gear wheel on the first mentioned shaft, teeth on the outer perimeter of said flanged wheel, a toothed wheel carried on threads on the end of said shaft, and a handle carried between said last mentioned wheel and said flanged wheel having dogs formed one on each side thereof, said dogs adapted to engage with either the teeth on the perimeter of the flanged wheel or with the teeth of the toothed wheel to rotate either wheel as necessary to lock the jack or to raise the lifting member as desired.

In testimony whereof I have affixed my signature.

ARTHUR DICKERSON.
